OSCAR M. LEICH, OF GENOA, ILLINOIS, ASSIGNOR TO CRACRAFT, LEICH ELECTRIC COMPANY, OF GENOA, ILLINOIS.

ANNUNCIATOR.

1,144,605.

Specification of Letters Patent. Patented June 29, 1915.

Application filed August 18, 1913. Serial No. 785,378.

To all whom it may concern:

Be it known that I, OSCAR M. LEICH, a citizen of the United States, residing at Genoa, in the county of Dekalb, and State 5 of Illinois, have invented a certain new and useful Improvement in Annunciators, of which the following is a full, clear, concise, and exact description, reference being had to the accompanying drawings, forming 10 a part of this specification.

My invention relates to annunciators and has for its object the provision of an improved relay annunciator, by which I mean an annunciator which may not only operate 15 a drop shutter, but which also has means to give or indicate code signals. In the operation, for instance, of small exchanges where the night operator is not constantly on duty, but only responds to a call, it is desirable 20 that the operator be informed whether he is wanted or not whenever a call enters the office. It may be stated that these smaller exchanges, in addition to the local lines entering therein, which are provided with but 25 one telephone, also serve as a terminus for a great many party lines. On these party lines it is generally the custom that whenever one ring is given central is wanted, and whenever two or more rings or any given 30 code signal is transmitted over the line that one of the other telephones on the same line is wanted and not the central operator. It is therefore desirable to have means which apprise the operator what character of signal 35 is coming into the office. In the general forms of annunciators or drops, the drops are provided with what are understood as night bell contacts, and whenever a shutter falls, the night bell rings. It is, of course, 40 plain that the shutter will respond whether one ring is being given or whether a plurality of rings or a code signal is being transmitted over the line. Consequently the operator would not know by hearing the night 45 bell alone what kind of signal is coming in and the operator would thus be called upon to answer each such call to ascertain if wanted. Of course, a great many of these calls at night are between parties on the 50 same line, and it is useless for the operator to respond to these calls.

My invention contemplates a provision of means whereby a signal, which I may also call a night bell, responds directly in accordance with the signals transmitted over

the line. Thus it will accurately retransmit a code call to which the operator knows that he need not respond. The operator is thus relieved from responding to any call except that particular call which indicates one 60 ring. My improved annunciator structure is of such a character and has means provided whereby the drops may be readily changed from the ordinary night bell to the code ringing type. 65

I will explain one form of carrying out my invention more in detail by referring to the accompanying drawings, in which—

Figure 1 is a side view, partly in section, of an annunciator unit provided in accordance with my invention; Fig. 2 is a top view of a bank, portions being broken away to reveal features of construction; Fig. 3 is a rear view of a portion of the mounting plate; Fig. 4 is a side view of my improved 70 drop structure; Fig. 5 is a rear view of a mounting plate adapted to receive a plurality of units; and Fig. 6 is a view diagrammatically to illustrate the circuit conditions involved. 80

My improved structure I have shown herein as forming part of a combined drop and jack structure, consisting of a mounting plate 1, to which all of the parts are mounted and from which all the parts except those 85 specifically referred to later are fully insulated. This insulation is done preferably by means of the insulating strips 2, 3 and 4, and through the use of insulated screws for mounting purposes, all as is readily apparent. To the front plate 1 and extending rearwardly thereof I have a framework 5, which carries an actuating coil 6 and which also carries the spring-jack 7, the spring-jack opening being suitably illustrated at 8. 90 A drop shutter 9 is provided which is controlled by the shutter arm 10 secured to the armature 11. The framework 5 has side walls 6^a, 6^a between which the armature 11 is pivoted and which also carry a bridge 12 100 of non-magnetic material. This bridge carries a pole piece 13 coöperating with the core 14 of the coil structure 6. The bridge 12 also carries a second pole piece of magnetic material 15, which is shown as being bent into an L-shape, referring more particularly to Fig. 1. This second pole piece 15 is adapted to coöperate with an armature 16 pivotally mounted at 17 between the side walls 6^a, 6^a. The armature 11 is pivotally 105 mounted at 18 between the side walls 6^a, 6^a. The armature 11 is pivotally 110

mounted at 18 between the side walls 6^a, 6^a. The armature 16 is fixedly secured to the pivoted element 19, which pivoted element carries an insulated spring 20. This spring 5 is more clearly shown in Figs. 4 and 6. This spring being fixedly secured to the movable element 19, moves in response to the actuation of the armature 16 and carries a contact point 21 at its lower extremity adapted 10 to co-act with a contact point 22 electrically connected to the front plate 1, as shown more clearly in Fig. 6. Platinum contact points are, of course, preferably provided for these contact-making elements. Thus, 15 whenever the armature 16 is energized, contact is established between the elements 21 and 22. The other extremity of the spring 20 is electrically connected by means of a spiral conductor 23 with a spring 24, which 20 spring is insulatingly mounted on the framework 5, as more clearly shown in Fig. 1. This spring 24 is in electrical contact with a conducting strip 25, insulatingly mounted upon the front plate 1. This conducting 25 strip has depending connectors 26, 26, so that contact may be made therewith along the sides of the banks of drops and jacks, for which purposes screw connectors 27 are provided, by which I mean that the banks 30 of drops are mounted in a board and instead of making a connection to each individual contact element 24 from without the board, it is only necessary to connect the outside wiring at the binding posts 27, to reach 35 each drop mechanism. This contact strip 25 is insulatingly mounted upon the front plate, as stated, but there is also interposed between this plate 25 and the front plate 1 a second conducting strip 28, which second 40 conducting strip is also insulated from the front plate 1, but which conducting strip 28 has downwardly extending fingers 29 projecting into an opening 30 provided in the front plate. These downwardly projecting 45 fingers 29 are normally used in connection with a finger 31 of the shutter 9 for the ordinary night bell purposes, the fingers 31 engaging the fingers 29 whenever the shutter 9 is released by the arm 10. Connectors 50 32 are provided at the opposite ends of the strip 28 so that connection may be made thereto at the opposite sides of the bank of drops and jacks. It will thus be seen that either the strip 25 or the strip 28 may be 55 connected in circuit so that the drop structure may either give the ordinary night bell indication or else give a code signal indication, as desired.

I might point out here that the arm 34 60 is provided with a lug 33, by means of which the shutter 9 is automatically restored whenever a plug enters the spring-jack structure, the lug 33 being raised so that the arm 34, pressing against the rounded extremity 35, pushes the shutter up-

wardly into the position shown in Fig. 1. This is true because the projecting arm 34 engages the element 35 of the drop shutter 9 forwardly of the pivotal mounting of said drop shutter so that a vertical movement of the arm 34 will swing this drop shutter contra-clockwise (Fig. 1) into its restored position. It will thus be apparent that whenever the armature 11 is actuated, the shutter 9 drops and contacts with the finger 29. The depending finger 31 of the shutter 9 rests directly forwardly of the projecting finger 29 and this projecting finger 29 is thus engaged by the finger 31 when the drop shutter 9 of Fig. 1 has fallen to its actuated position. This, however, will not cause the operation of a night bell so long as no battery, source of current and signal are connected to the plate 28. Whenever the armature 11 is actuated, the armature 16 is also actuated and this completes a circuit between the elements 21 and 22 which conforms directly to the number of rings or more specifically to the particular code signal received by the coil structure 6. Thus to use the relay armature, electrical connection is made with the plate 25, and this is preferably done as shown diagrammatically in Fig. 6, in which case the circuit can be traced as follows: from the battery 36 through conductor 37, relay 38, conductor 39, front plate 1, contact 22, contact 21, spring 20, coil conductor 23, spring 24, conducting plate 25 and conductor 40, back to the battery 36. This energizes the relay 38 100 to thereby actuate its armature 41 to close circuit through the local signal 42 and battery 43. I use the relay 38 because it will hold up between impulses even though the armature 16 might vibrate in response to the incoming signal current, which is usually of an alternating or pulsating character. I, of course, have the spring 20 which already to a large extent compensates for this possible fluttering of the armature 16, 110 as the spring action of this spring 20 assists in maintaining a more or less continuous closure of the contacts 21 and 22. However, the relay 38 may be more or less slow acting, if desired, so as to maintain a more 115 perfect closure of the local signal circuit than would otherwise be possible.

From what has been described the nature of my invention will be clear. It will also be readily apparent that the particular structure and arrangement set forth serves for illustrative purposes without thereby limiting the broad character of the invention.

Having, however, thus described one form 125 which my invention may take, what I claim as new and desire to secure by Letters Patent is:

1. An annunciator for telephone switchboards having an actuating coil, two sig- 130

- nals under the control thereof, and means interposed between said signals and said coil to operate one signal irrespective of the nature of the energization of said actuating 5 coil and to operate the other signal in accordance with a code signaling indication.
2. An annunciator for telephone switchboards having a front plate, a framework mounted rearward of said front plate and 10 insulated therefrom, an actuating coil carried by said framework, a shutter, an armature under the control of said coil to control said shutter, a second armature mounted upon said framework and controlled by said 15 coil, a contact spring carried by said second armature and insulated therefrom, and a conducting element mounted upon but insulated from said framework and electrically connected with said spring.
- 20 3. An annunciator for telephone switchboards having a front plate, a framework mounted rearward of said front plate and insulated therefrom, an actuating coil carried by said framework, a shutter, an armature under the control of said coil to control said shutter, a second armature mounted upon said framework and controlled by said 25 coil, a contact spring carried by said second armature and insulated therefrom, a conducting element mounted upon but insulated from said framework and electrically connected with said spring, and a conducting strip mounted upon but insulated from said 30 front plate with which said conducting element has electrical contact.
- 35 4. An annunciator for telephone switchboards having a front plate, a framework mounted rearward of said front plate and insulated therefrom, an actuating coil carried by said framework, a shutter, an armature under the control of said coil to control said shutter, a second armature mounted upon said framework and controlled by said 40 coil, a contact spring carried by said second armature and insulated therefrom, a conducting element mounted upon but insulated from said framework and electrically connected with said spring, a conducting strip mounted upon but insulated from said 45 front plate with which said conducting element has electrical contact, and a contact element having electrical connection with said front plate adapted to coöperate with said contact 50 spring.
- 55 5. An annunciator bank for telephone switchboards having a drop shutter, a common conducting plate for said bank adapted for electrical engagement with said shutter when said shutter is released, a second common conducting plate for said bank, an actuating coil, and means under the control of said actuating coil to control said shutter and to control the electrical circuit through 60 said second conducting plate.
6. An annunciator bank having an actuating coil, two signals under the control thereof, and means interposed between said signals and said coil to operate one signal irrespective of the nature of the energization of said actuating coil and to operate the other signal in accordance with a code signaling indication, said means including 65 two armatures for said coil, one for each signal.
7. An annunciating system of the character described having an actuating coil, a shutter adapted when actuated to convey a permanent signal, an armature under the control of said coil to control said shutter, a second armature under the control of said 70 coil, a local signal circuit controlled by said second armature, and means interposed between said second armature and said local signal circuit to nullify the fluttering actuation of said second aforesaid armature in 75 response to a fluctuating current to thereby get a steady control of said local signal circuit.
8. An annunciating system of the character described having an actuating coil, a shutter adapted when actuated to convey a permanent signal, an armature under the control of said coil to control said shutter, a second code responsive armature under the control of said coil, a local signal circuit 80 controlled by said second code responsive signal, and means interposed between said second code responsive armature and said local signal circuit to nullify the fluttering actuation of said second aforesaid code responsive armature in response to a fluctuating current to thereby get a steady control 85 of said local signal circuit.
9. An annunciating system of the character described having an actuating coil, a shutter adapted when actuated to convey a permanent signal, an armature under the control of said coil to control said shutter, a second code responsive armature under the control of said coil, a local signal circuit 90 controlled by said second code responsive signal, and means interposed between said second code responsive armature and said local signal circuit to nullify the fluttering actuation of said second aforesaid code responsive armature in response to a fluctuating current to thereby get a steady control 95 of said local signal circuit.
10. In witness whereof, I hereunto subscribe my name this 19th day of July, A. D., 1913. 100
- OSCAR M. LEICH.
